J. C. MINGES.

METHOD OF MAKING SHOES.

APPLICATION FILED JULY 10, 1916.

1,208,613.

Patented Dec. 12, 1916.

UNITED STATES PATENT OFFICE.

JOSEPH C. MINGES, OF HIGHLAND, ILLINOIS, ASSIGNOR OF ONE-FOURTH TO FREDERICK J. HOCKMUTH AND ONE-FOURTH TO ALVIN C. MINGES.

METHOD OF MAKING SHOES.

1,208,613.

Specification of Letters Patent. Patented Dec. 12, 1916.

Application filed July 10, 1916. Serial No. 108,440.

To all whom it may concern:

Be it known that I, JOSEPH C. MINGES, a citizen of the United States of America, a resident of Highland, in the county of 5 Madison, State of Illinois, have invented certain new and useful Improvements in Methods of Making Shoes, of which the following is a full, clear, and exact description, reference being had to the accompanying 10 drawings, forming a part of this specification.

My invention relates to improvements in the art of making shoes, one of the objects being to provide a simple method of making 15 shoe uppers, so as to reduce the cost of manufacturing shoes, by avoiding the expense of attaching the lining sections to the facings before securing the linings to the quarters, at the same time eliminating the loss which 20 has heretofore been due to ill fitting linings.

Another object is to provide a simple method of stiffening the uppers without adding the usual fabric stiffeners to the 25 shoes.

To clearly point out the advantages of my method, I will first describe some of the 30 steps involved in the usual method of making shoes.

Heretofore, the leather quarters have been 35 formed by suitable dies and afterward sewed together in pairs before attaching the fabric linings to the leather. It is customary to form a row of stitching in each quarter at a distance from the front edge thereof corresponding approximately to the 40 width of a side facing. These stitches, known as "eyelet row stitching" are merely ornamental and do not attach anything to the quarters. I attach the inner margins of the side facings to the lining and quarters, by means of the "eyelet row stitching" and thereby eliminate the cost of one operation, 45 as will be hereinafter described.

In following the ordinary or usual 50 method, the fabric lining members are assembled, stitched to the facings, and thereafter secured to the leather quarters. The usual practice is to cut a large number of fabric lining members at a single operation, by forcing a die through a pile of superimposed fabric layers. The stretching and buckling of the fabric as the die is forced 55 through the pile produces irregularities and differences in the sizes of the linings, which

cause considerable difficulty in assembling 55 the linings with the leather portions of the shoes. Heretofore, the first step in assembling the complementary lining halves has usually consisted in connecting the lining elements to each other through the medium 60 of an inner back stay, two rows of stitches being formed in the stay to secure the lining halves thereto. It is quite difficult to hold the lining members and back stay in the proper relative positions during these 65 stitching operations, but it is very important that they should be properly positioned, otherwise it will be necessary to stretch the lining on one side while it is being secured to the upper and this will spring or distort 70 the back stay.

When the complementary lining halves are secured to the back stay, the side facings are stitched to the front edges of the lining members, and thereafter a top facing is 75 stitched to the upper edges of said lining members. Considerable care must be exercised in sewing on the top facing without wrinkling or stretching either of the fabric lining members. Owing to the irregularity 80 of the shape of the lining which should conform precisely to the shape of the upper portion of a finished shoe, a very high degree of skill is required in making the ordinary linings and the trained operators 85 cannot assemble and attach the various elements to the lining members without making a large number of "seconds". Many of such linings are applied to shoes with the result of greatly reducing the value thereof. 90

When the lining is completed in the usual manner by stitching the fabric members to the facings, it is ready to be attached to the leather quarters, and is placed thereon. A line of stitching is then formed along the 95 outer edge of one side facing, across the upper edge of the top facing and down the outer edge of the other side facing, so that the lining is secured by stitches at the outer margins of the quarters and facings. This 100 marginal row of stitching is formed while the parts are laid out upon the table of a sewing machine and it will be apparent that when the lined upper is bent to form the top of the shoe there will be more or less wrinkling of the lining.

In following my method it is not necessary to connect and assemble the irregular

linings and facings before attaching them to the quarters, and it is not necessary to exercise a high degree of care and skill in handling the lining. If only reasonable care is exercised, ordinary operators can readily produce the lined quarters without wrinkling the linings, and without reducing the value of any of the shoes on account of lining defects.

16 Figure I is a detail view showing a lining member secured to a quarter. Fig. II is a view similar to Fig. I showing the complementary lined quarters attached to each other. Fig. III is a view showing the inside 15 of the lined quarters after the facings and back stays have been secured thereto, one of the lining members being broken out to show a portion of one of the quarters.

In carrying out my method the quarters 1 20 may be cut by dies in the usual manner, and the lining members 2 may also be formed in the usual manner. The first step in assembling the parts preferably consists in securing each lining member 2 to one of the quarters 1, as shown in Fig. I. These lining members are preferably secured by cementing the same throughout substantially the entire area in which they contact with the flesh side or inner side of the quarters, 25 thereby stiffening the uppers without the use of an added fabric element and at the same time avoiding wrinkling or buckling of the lining. When a lining member 2 is attached to one of the quarters 1, as shown 30 in Fig. I, it will conform precisely to the quarter, and it will be apparent that such attachment may be made by an ordinary operator without the exercise of a high degree of skill.

40 After the lining members 2 have been attached to the quarters, a pair of complementary lined quarters are placed one above the other with their outside faces contacting, as shown in Fig. II, and the back seam 5 is 45 then formed preferably by stitching through the linings and quarters so as to unite the pair of lined quarters at their rear edges. The lined quarters are then spread out, as illustrated in Fig. III, and the facings 6 and 7 are attached thereto. To accomplish 50 this a substantially continuous line of stitching is formed at the inner and outer margins of the facings, as indicated by arrows in Fig. III. After forming the row 55 of stitches 8 along the outer margin of the side facing 6 at the left side of Fig. III, so as to attach said side facing to the outer edge of a quarter 1, the row of stitches 9 are formed to secure the upper edge of the 60 top facing 7 to the upper edges of the quarters 1. Thereafter the row of stitches 10 are formed to attach the outer edge of the other side facing 6 to the other quarter 1. The inner row of stitches 10', 9' and 8', parallel 65 with the rows of stitching 10, 9 and 8, pass

through the inner margins of the facings, and also through the lining and quarters.

It will be noted that the stitches 8' and 10' constitute the "eyelet row stitching" and also serve as means for stitching the side 70 facings to the lining and the quarters, instead of being merely ornamental stitches. Before forming the row of stitches 9', the upper edge of the inner back stay 12 is inserted between the top facing and the lining 75 members so that the stitches 9' will secure the upper portion of said back stay to the other elements of the shoe. Thereafter an outer back stay 13 may be applied to the outer faces of the lined quarters. Stitches 80 14 pass through the inner and outer back stays and also through the lining and quarters. It will be observed that in following my method it is not necessary to make the irregular lining structure which has heretofore involved considerable time and labor and which has been difficult to manipulate during the various operations. By making the lined quarters as independent units 85 (Fig. I) each lining member will be accurately fitted to the inner face of the quarter. The eyelet row stitches 8' and 10' are utilized to perform the functions of uniting the quarters, linings, and side facing. Furthermore, if the lining members 2 are cemented 90 to the quarters, as previously described, it will be unnecessary to use the fabric stiffeners which have heretofore been placed between the lining and quarters for the purpose of reinforcing or stiffening the latter. 100

I claim:

1. The method of making shoes which comprises cutting quarters and lining members therefor, securing the lining members to the respective quarters to produce a pair of 105 lined quarters, securing the lined quarters to each other, securing facings to the lined quarters by stitching through the linings, facings and quarters, and thereafter finishing the shoe.

2. The method of making shoes which comprises cutting quarters and lining members therefor, securing the lining members to the respective quarters to produce a pair of lined quarters, each lined quarter of the pair being free of connection with the other lined quarter, then securing the lined quarters to each other by stitching through the rear margins of the quarters, securing facings to the lined quarters by stitching through outer 110 margins of said facings and quarters and also by stitching through the quarters, linings and inner margins of the facings, and subsequently finishing the shoe.

3. The method of making shoes which 115 comprises forming quarters and lining members therefor, thereafter attaching a side facing to each lining member by stitching through the inner margin of the side facing and through the lining member and quarter, 130

thereby forming the eyelet row stitching on the outer face of the quarter, and subsequently finishing the shoe.

4. The method of making shoes which comprises cutting quarters and lining members therefor, securing the lining members to the respective quarters to produce a pair of lined quarters, thereafter attaching the lined quarters to each other, securing a top facing to the lined quarters by stitching through the lining members, top facing and quarters after the lined quarters have been attached to each other, and thereafter finishing the shoe.

15 5. The method of making shoes which comprises cutting the quarters and lining members corresponding thereto, cementing the lining members to the respective quarters, securing the back edges of the quarters together by a row of stitching, securing side and top facings to the linings and quarters by parallel lines of stitching disposed respectively adjacent to the inner and outer edges of said facings, and subsequently finishing the shoe.

20 6. The method of making shoes which comprises securing lining members to their respective quarters by cementing the same

throughout substantially the entire area of their contacting faces whereby the uppers 30 will be stiffened and wrinkling of the lining avoided, thereafter stitching the lined quarters together, and subsequently completing the shoe.

7. The method of making shoes which 35 comprises securing lining sections to their respective quarters by cementing said lining sections directly to the inner or flesh side of the quarters, placing the grain sides or outer sides of the complementary quarters 40 together and forming a back seam by a line of stitching passing through the lined quarters adjacent to the back edges thereof, and subsequently completing the shoe.

8. The method of making shoes which 45 comprises securing lining members to the quarters by cementing said members directly to the inner or flesh side of the quarters, uniting the quarters by a back seam, positioning an inner back stay on the lining 50 members symmetrically with the back seam, securing all of said parts together by parallel lines of stitching passing through the back stay lining members and quarters, and subsequently completing the shoe.

JOSEPH C. MINGES.
